(57) **CLAIM**

The ornamental design for a footwear outsole, as shown and described.

DESCRIPTION

FIG. 1 is a perspective view of a footwear outsole showing my new design;

FIG. 2 is a bottom plan view thereof;

FIG. 3 is a top plan view thereof;

FIG. 4 is a front elevational view thereof;

FIG. 5 is a rear elevational view thereof;

FIG. 6 is a first side elevational view thereof; and,

FIG. 7 is an opposite side elevational view thereof.

The broken lines in FIGS. 1-7 showing the remainder of the footwear illustrate the environment in which the design resides. The broken lines form no part of the claim. The dot-dash lines around and within the solid-line area define the boundary of the claim. The dot-dash lines form no part of the claim.
